UNITED STATES PATENT OFFICE.

LLOYD A. SWINEFORD, OF ASHLAND, OHIO.

SWIMMER'S FLOAT.

Application filed March 7, 1922. Serial No. 541,700.

To all whom it may concern:

Be it known that I, LLOYD A. SWINEFORD, a citizen of the United States, residing at Ashland, in the county of Ashland and 5 State of Ohio, have invented a new and useful Swimmer's Float, of which the following is a specification.

This invention relates to swimming devices, and has for its object the provision of 10 an improved means for sustaining a bather in the correct swimming position in the water, whereby the bather is free to coordinate the proper movements of his arms and legs in learning the art of swimming.

15 A further object of the invention is the provision of an improved device which is compact, simple and efficient, and which comprises a casing having two or more compartments, each forming a pocket for 20 the reception of an inflatable balloon or bladder devoid of the usual valve, the casing being adapted to be worn on the back of the bather.

The invention will be best understood 25 from a consideration of the following detailed description taken in connection with the accompanying drawing forming part of this specification, with the understanding, however, that the invention is not confined 30 to any strict conformity with the showing in the drawing, but may be changed and modified so long as such changes and modifications mark no material departure from the salient features of the invention as expressed in the appended claims.

In the drawing:—

Fig. 1 is a view in perspective of my improved float secured upon the back of a bather.

40 Fig. 2 is a fragmentary view in elevation of one form of my invention.

Fig. 3 is a view in elevation of a modified form.

45 Fig. 4 is a vertical section of a single compartment of the float taken along the line 4—4 of Fig. 3.

Fig. 5 is a horizontal section of the float taken along the line 5—5 of Fig. 3.

Referring to the drawing, 1 designates a 50 fabric casing which is preferably formed by folding a single piece of fabric of suitable length and width upon itself at 2, and stitched adjacent the edge 2, at 3. The lower edges of the folded fabric are cut away in such a manner as to form two curved bottom portions 4, the line of stitch-

ing 3 being continued around these curved bottom portions and up the longitudinal side edge 5. The upper edges of the sides of the casing are free of stitching, thereby providing an opening or entrance to the interior of the casing. As shown in Fig. 3, a row of stitching 6 is placed intermediate the longitudinal side edges 2 and 5 of the casing, whereby the two sides of the casing are 60 joined together to form two open-ended pockets 7 and 8.

In my preferred form shown more particularly in Fig. 2, I provide each opposite side 9 and 10 with a row of eyelets 11 arranged along the longitudinal center of said sides and connected by a lace 12 whereby the two pockets or compartments 7 and 8 are formed, the lacing in this instance replacing the stitching 6 of the other form. 70

The upper edges of the rear sides 9 of the casing are provided with flaps 13 and 14 which are respectively adapted to provide 75 closures for the openings of the pockets 7 and 8, each flap being provided with a button hole 15 adapted to be engaged by a button 16 sewed to the front or outer side 10 of the casing.

An elongated inflatable member 17, resembling in appearance and construction 85 the well known elongated toy rubber balloon, is adapted to be inserted within each of the pockets 7 and 8, and inflated by forcing air or gas through a nipple 18 formed at one end of the bladder 17. When 90 said bladder is sufficiently filled, the nipple 18 may be made air-tight in the usual manner, that is, its sides are compressed or pinched together by a cord wrapped tightly around the nipple and knotted. This simple 95 construction of nipple and clamping cord eliminates the use of valves which invariably permit air to escape from the inflated member.

The rubber balloon or bladder is made 100 sufficiently strong and reliable so that it will not readily burst or be punctured, while the rubber is of such a composition that it will not readily be affected by the water.

A strap 19 is secured intermediate its ends, 105 as shown at 20 in Fig. 4, to the upper edge of the rear side 9 of the casing and just below the juncture of the lower edges of the flaps 13 and 14, and said rear side of the casing. The ends of these straps are secured 110 at 21 to the longitudinal side edges 2 and 5 of the casing and at a point below the upper

edge of said casing, whereby two loops 22 and 23 are formed through which the arms of the bather are adapted to be slipped, and which loops encircle the shoulders of said bather.

A strap 24 is secured transversely of its ends to the rear side 9 of the casing 1, and midway between the upper and lower edges of said casing, so that the free ends 25 and 26 of said strap may encircle the waist of the bather and be tied in front, whereby the loops 22 and 23 and the strap 24 will maintain the bather's float upon the back of the bather, as shown in Fig. 1 of the drawing. Some form of buckle may be employed to connect the ends of the strap 24, if desired.

By securing the intermediate portions of straps 19 and 24, which span the full width 20 of the back of the casing, to the casing, the straps are properly reinforced against separation from the casing.

It will be seen from Fig. 1, that when the float is applied to the back of a bather, there 25 will be no abrupt ends to be pushed through the water and retard the progress of the swimmer. Furthermore, the length of the float and the position of the float upon the back of the bather is such, that it will sustain the bather at the proper swimming 30 angle in the water, so that the bather, with the element of danger of sinking eliminated, is only required to concentrate his mind upon coordinating the movements of his 35 arms and legs in the proper mode of swimming.

A float of the average size is capable of supporting a weight of at least two hundred pounds.

What is claimed is:—

1. A swimmer's float comprising a two-sided fabric casing open at one end and closed at the other end and both sides by stitching, fastening means disposed longitudinally and centrally and connecting each

side of the casing so as to divide the casing into two open-ended compartments placed side by side, an elongated inflatable member insertable within each compartment, a flap for closing each compartment, and means 50 for securing the casing to the body of the wearer.

2. A swimmer's float comprising an open-ended fabric casing divided intermediate its longitudinal edges into a pair of pockets, a closure for the open end of each pocket, an elongated rubber bladder insertable within each pocket, a strap secured intermediate its ends to the upper end of the casing adjacent the closures, the free ends of the strap 60 being secured to the longitudinal edges of the casing at a point below the upper edge of the casing whereby loops are provided for the reception of the arms of the bather, and a second strap secured intermediate its 65 ends to one side of the casing, the free ends of the strap adapted to surround the body of the bather and be secured together to support the casing and its contained inflatable members on the back of the bather. 70

3. A swimmer's float comprising a two-sided one-piece fabric casing open at one end and having a row of aligned eyelets disposed longitudinally and centrally in each side of the casing, a lace threaded through the eyelets and dividing the casing into two open-ended compartments, an elongated inflatable member insertable within each compartment, flaps extending from the upper edge of one side of the casing and adjacent the open 75 ends of each compartment, said flaps adapted to be closed over the open ends and secured to the opposite sides of the casing, and means for securing the casing to the body of a wearer. 80

In testimony, that I claim the foregoing as my own, I have hereto affixed my signature.

LLOYD A. SWINEFORD
